(57) **CLAIM**

We claim the ornamental design for a truck bed liner, as shown and described.

DESCRIPTION

FIG. 1 is a bottom perspective view of a truck bed liner according to our design;

FIG. 2 is an enlarged bottom perspective view of our design;

FIG. 3 is a sectional view taken along Line 3-3 of FIG. 2;

FIG. 4 is an enlarged front view of our design, a back view thereof being a mirror image of the front view;

FIG. 5 is an enlarged left side view of our design, a right side view thereof being a mirror image of the left side view; and,

FIG. 6 is an enlarged bottom view of our design.

A top surface of the truck bed liner is unadorned and forms no portion of the claimed design. The outer broken line shown in FIG. 1, and the horizontal broken line shown in FIG. 3, are directed to environment and are for illustrative purposes only. The inner broken line shown in FIG. 1, the broken lines shown in FIGS. 2 and 6, and the vertical broken lines shown in FIG. 3, represent the bounds of the claimed design. The broken lines form no part of the claimed design.
